MOLDED CARTON FOR FRAGILE ARTICLES

Walter H. Randall, Waterville, Maine, assignor, by mesne assignments, to The Canal National Bank of Portland, Portland, Maine, and William B. Nutley, Portland, Maine, as trustees

Application December 24, 1947, Serial No. 793,681

3 Claims. (Cl. 229—2.5)

1

This invention relates to cartons for packaging fragile articles, and particularly to a carton made of molded pulp for packaging eggs. Such cartons are generally used in grocery stores as take-home packages for eggs bought by the dozen, but may also be used for the shipment and storage of eggs.

These cartons usually consist of a pair of co-extensive tray-like sections of the required size and depth which are hinged together along their adjacent longitudinal edges so as to overfold upon one another and provide a closed pack.

One section is an egg-holding section and is provided with molded formations providing individual pockets for holding the required number of eggs.

The other section is a cover section which is usually devoid of pocket-defining formations so as to present a smooth, flat uninterrupted top surface well suited to receive printing. Due to the absence of pocket-defining formations, however, this cover section is neither as rigid nor as strong as the egg-holding section which contains such formations, and accordingly one important object of my invention is to provide a molded pulp carton the cover section of which will not only present a flat, smooth surface that is well adapted to receive printing but which section will also possess the required stiffness and rigidity to prevent it from collapsing or distorting when the closed carton is subjected to downward pressure, as where the closed cartons are stacked in superimposed layers.

One effect of such downward collapsing pressure on a closed carton is to cause the cover section to slide laterally outwardly relative to the egg-holding section, thereby bringing its free edge, i. e., the edge which is distant from the edge that is hingedly connected to the egg-holding or base section, out of line with the corresponding free edge of the egg-holding section, and accordingly another important object of my invention is to provide the carton with an interlock which effectively resists this tendency of the sections to slide laterally relative to one another when the closed carton is subjected to downward collapsing pressure.

Other objects and advantages will appear as this description proceeds.

In the accompanying drawing wherein I have illustrated a preferred embodiment of my invention.

Fig. 1 is a perspective view of a molded pulp egg carton in accordance with my invention, the carton being open, and

2

Figs. 2 and 3 are sections on the lines 2—2 and 3—3 respectively of Fig. 1 as seen when the carton is closed and turned end for end from the position shown in Fig. 1.

In the form of my invention herein illustrated my carton is designed to carry one dozen eggs in two spaced parallel rows of six eggs each. In constructing such a carton, I prefer to proceed as follows:

I mold an integral sheet of pulp contoured to provide a pair of tray-like sections 10 and 11 of the required size and depth. Sections 10 and 11 are coextensive with each other at their adjacent longitudinal edges and are hingedly connected along adjacent longitudinal flanged portions at the longitudinal center line of the sheet as indicated at 12 so that when overfolded upon one another they provide a closed pack. Each section consists of a bottom wall and angularly extending side and end walls continuously enclosing the same, said side and end walls terminating in peripheral flanges in the plane of the sheet, which flanges constitute meeting surfaces for the cover and base sections when the cover section is overfolded upon the base section.

The section 10 of my novel carton is an egg-holding or base section and, when designed to carry one dozen eggs in two rows of six eggs each, is formed with a central row of spaced upstanding hollow posts 13 and 14 preferably of frusto-conical form, arranged in line from end to end of section 10. As shown, there are five full posts 13 and two half-posts 14, the latter being located at the ends of section 10 and merging with the end walls of said section.

The opposite side wall portions of section 10 are each formed with a row of spaced inwardly projecting hollow half-posts 15 and 16, preferably also of frusto-conical form. Half posts 15 and 16 are located opposite the central row of posts and define with said central row and with each other and with the adjacent portions of the side, end and bottom walls of section 10 two spaced rows of closed-bottom pockets 17, six pockets to each row, within which the eggs are supported by wedging contact with the side walls of the full posts 13 and the half-posts 14, 15 and 16.

The bottoms of the egg pockets are preferably cushioned by forming the bottom wall of section 10 with raised cushioning formations 18 and the pockets are further separated from each other at a suitable distance above their bottoms by a single row of longitudinally extending hollow ribs 19 connecting said central row of posts 13 and 14 to one another and by five rows of trans-

versely extending hollow ribs 20 connecting said half-posts 15 and 16 to said central row of posts and to the side walls of section 10. In addition to their function of separating the individual pockets from each other said rows of ribs 19 and 20 also strengthen and stiffen said carton section. The tops of all posts 13, 14 and 15 and the tops of all posts 16, except the posts designated 16a and 16b terminate in the same plane, which is the plane of the sheet. The tops of posts 16a and 16b terminate in a plane slightly lower than the plane of the sheet to provide with the adjacent portions of said side wall a pair of spaced locking recesses.

The other section 11 of my novel carton is a generally flat-bottomed cover section and the opposite side wall portions thereof are each provided with a longitudinally extending row of spaced inwardly extending oppositely disposed hollow ribs or stiffening elements 21 and 22. The stiffening elements 21 and 22 are likewise located opposite the half-posts 15 and 16 of the egg holding section 10 so that the top ends of elements 22 will abut the top ends of the half posts 15 and the top ends of elements 21 will abut the top ends of half-posts 16 when the sections are overfolded to close the carton and provide in effect a plurality of spaced strengthening struts from top to bottom of the carton. Preferably the stiffening elements 21 and 22 extend vertically of the side wall portions of cover section 11 from top to bottom thereof and taper from their bases where they merge with the bottom wall of said section towards the upper edge of said side wall, terminating at their upper ends in substantially the plane of the sheet.

The primary function of the ribs or stiffening elements 21 and 22 is to strengthen and stiffen the side walls of the cover section. However, two of the stiffening elements 21, here designated 21a and 21b, in the side wall portion of cover section 11 which is distant from the fold line of the carton extend beyond the plane of the sheet and are formed at their upper ends to interlock within the locking recesses afforded by the flat tops of the pair of slightly lowered half posts 16a and 16b in the distant side wall of egg holding section 10 when the carton is closed. Such interlock may be had by forming the upper ends of said stiffening elements 21a and 21b as enlarged locking projections 23 and 24 which when the carton is closed cooperate with the inner surface of the outer wall of the base section, whereby when the carton is closed, lateral movement of the outer side wall of the cover section beyond the adjacent outer side wall of the base section is prevented. As shown, the projections 23 and 24 abut the portions of the side wall of the egg-holding section above the flat upper ends of the slightly lowered half-posts 16a and 16b of said section 10.

Thus, when the closed cartons are stacked in superimposed layers or otherwise subjected to downward pressure which tends to cause the cover section to slide laterally outwardly relative to the egg-holding section, the tendency of the free edge of the cover section to move outwardly out of line with the corresponding edge of the egg-holding section is resisted by the abutment of the projections 23 and 24 with the side wall portions of the egg-holding section adjacent the tops of the lowered posts 16a and 16b.

While I have shown two of the stiffening ribs 21 and two of the half-posts 16 as formed to cooperate with each other in preventing lateral

sliding movement of the cover section relative to the egg-holding section, it will be understood that I am not to be restricted to any particular number of interlocking formations.

It will be noted that as a result of my construction the cover section is adequately stiffened against collapse while at the same time presenting between the stiffening elements 21 and 22 a continuous, uninterrupted flat surface well adapted to receive printing.

While I have shown a preferred arrangement of pocket defining formations and a preferred arrangement of cover-stiffening formations in which certain of the stiffening formations coact with certain of the pocket-defining formations to provide an interlock, I recognize that the disclosed arrangement may be varied considerably and still achieve my advantages.

It will likewise be understood that while I have described my carton as being made of molded pulp and adapted to carry one dozen eggs arranged in two spaced parallel rows of six eggs each, such disclosure is by way of illustration and not limitation. Obviously, my carton may be made of other materials and may be designed to carry larger or smaller numbers of eggs or other fragile articles in any desired arrangement of rows, as for example, to carry one dozen eggs in three rows of four eggs each. Other equally desirable arrangements for carrying larger or smaller quantities of eggs or other fragile articles will readily suggest themselves to those skilled in the art.

I claim:

1. A carton for eggs and the like comprising an integral sheet of molded pulp contoured to provide a tray-like base section and a tray-like generally flat-bottomed cover section each having side and end walls terminating in peripheral flanges in the plane of the sheet, said flanges constituting meeting surfaces for the cover and base sections when the cover section is overfolded upon the base section, said cover and base sections being hingedly secured together along adjacent longitudinal flanged portions, the side walls of said cover section being provided with inwardly extending ribs extending from the bottom of the cover section to the plane of the sheet, at least one of the ribs on the outer side wall of the cover extending beyond the plane of the sheet to cooperate with the inner surface of the outer side wall of the base section, whereby when the carton is closed, lateral movement of the outer side wall of the cover section beyond the adjacent outer side wall of the base section is prevented.

2. A carton for eggs and the like comprising an integral sheet of molded pulp contoured to provide a tray-like base section and a tray-like generally flat-bottomed cover section each having side and end walls terminating in peripheral flanges in the plane of the sheet, said flanges constituting meeting surfaces for the cover and base sections when the cover section is overfolded upon the base section, said cover and base sections being hingedly secured together along adjacent longitudinal flanged portions, the side walls of said cover section being provided with inwardly extending ribs extending from the bottom of the cover section to the plane of the sheet, a plurality of the ribs on the outer side wall of the cover extending beyond the plane of the sheet to cooperate with the inner surface of the outer side wall of the base section, whereby when the carton is closed,

lateral movement of the outer side wall of the cover section beyond the adjacent outer side wall of the base section is prevented.

3. A carton for holding a group of fragile articles, said carton comprising an integral sheet of molded pulp contoured to provide a pocketed base section hingedly secured to a flat bottomed tray-like cover section, each section having outwardly extending marginal flanges defining meeting surfaces in a common plane when the sections are folded together at their hinge, the base section having a plurality of partition ribs and posts defining a number of pockets corresponding to the number of articles in said group, the cover section having a plurality of inwardly directed strengthening ribs extending the entire depth of a cover side wall opposite to the hinge, at least one of said strengthening ribs having its end adjacent the flange, shaped to form with the flange an outwardly opening groove in which a portion of the base section flange is interlockingly received to furnish a spread-reducing interlocking engagement between the ribs on the cover side wall and

the corresponding side wall of the base section to cause the rigidifying effect of the base partitions and posts to combine with the rigidifying effect of the ribs in preventing the cover's being squeezed out over the side of the base section.
